JAMES F. DORAN, OF DANBURY, CONNECTICUT

HAT-CLIPPING MACHINE

Application filed September 20, 1927. Serial No. 220,691.

This invention relates to machines for clipping hats, such as "velours," having protruding hair and fur fibres.

One of the objects of the invention is to provide a hat clipping machine which is thoroughly practical and highly efficient. Another object is to provide a machine of the above nature capable of rapid and accurate operation. Another object is to provide a machine of the above nature which does not require the attention of a skilled operator and which will uniformly clip the nap of velour hats or the like to a predetermined length. Another object is to provide a machine of the above nature which is simple in construction and thoroughly dependable in operation. Other objects will be in part obvious or in part pointed out hereinafter.

The invention accordingly consists in the features of construction, combinations of elements, and arrangement of parts which will be exemplified in the structure to be herein-after described and the scope of the application of which will be indicated in the following claims.

In the accompanying drawings in which is shown one of the various possible embodiments of this invention,

Figure 1 is a side elevation, certain parts being broken away to better show the structure;

Figure 2 is a detail view showing the mounting of the clipping device;

Figure 3 is a top plan view of the machine with parts thereof broken away;

Figure 4 is a detail view showing a portion of the driving mechanism;

Figure 5 is a plan view of an arm upon which is supported the clipping device, and

Figure 6 is a side elevation of the parts shown in Figure 5.

Similar reference characters refer to similar parts throughout the several views of the drawings.

Referring now to the drawings in detail, and first to Figures 1 and 3, the machine shown herein is mounted upon a suitable base comprising what may be termed a table or platform 11, supported at a suitable height by legs 12 which are braced by cross members

such as 13. Projecting upwardly from the base 11 is a supporting casting or frame 14 at the upper end of which is formed a bearing 15 for rotatively supporting a driving shaft 16. In front of the driving shaft 16, and preferably substantially axially aligned therewith is a shaft 17 which is rotatively supported in a bearing 18 formed in the front end of the supporting frame 14. The shaft 17 is adapted to be rotated from the driving shaft 16, as will be described more particularly herein-after, and the shaft 17 is in turn adapted to rotate a hat block 19 upon which is positioned the hat 20 to be clipped.

The driving shaft 16 is rotated at a rate of speed suitable for rotation of the hat while being clipped, and this drive may be effected by any suitable means. Preferably, there is mounted upon the rear of the machine an electric motor 21 which, by means of a belt 22 drives a pulley 22^a mounted upon a shaft 22^b. The shaft 22^b is rotatively supported in the bottom portion of a housing 16^a which is positioned at the rear end of the shaft 16. The shaft 22^b drives the shaft 16 through suitable reduction gearing positioned within the housing 16^a; this gearing conveniently takes the form of a worm drive through which the shaft 16 is slowly rotated from the rapidly rotating motor 21.

The driving shaft 16 has secured thereon adjacent its forward end, and adjacent to the middle portion of the supporting frame 14, a worm gear 23. The worm gear 23 is adapted to mesh with and drive a worm wheel 24 which is supported upon a shaft 25 and rests beneath the worm gear in an opening in the frame 14. The worm wheel 24 is thus rotated at a slow rate of speed about the axis of the supporting shaft 25.

Connected to the worm wheel 24 by a bolt 26 engaging a slot 27 therein is a forwardly extending crank arm 28 which is connected by a bolt 29 at its forward end to an upstanding bracket 30 secured to a bar 31. The bar 31 is slidably supported for longitudinal sliding in suitable bearing supports 32 and 33. By means of the crank arm 28, the worm wheel 24 is adapted thus to slowly reciprocate the bar 31 in its bearings 32 and 33. The

length of these reciprocations may be adjusted by moving the position of the bolt 26 in the slot 27; also the locus of movement of the bar 31 may be adjusted by changing the position of the bracket 30 lengthwise of the bar, this bracket being adjustably clamped upon the bar by a clamping screw 34.

The forward bearing 33 for the sliding bar 31 is mounted upon an arm or bracket 35 extending forwardly from the frame substantially beneath the hat support. Mounted to swing about a vertical axis in the outer end of the supporting arm or bracket 35 is an outwardly projecting horizontal arm 36. The arm 36 is provided with a projecting hollow spindle or bearing portion 36^a which is rotatively supported in the hollow vertical portion 35^a of the bracket 35 thereby to pivot the arm 36, the lower end of part 36^a being provided with locking nuts 36^b. The forward end portion of the sliding bar 31 is provided with gear teeth 31^a (Figure 3) forming a rack. This rack meshes with a gear 37 secured to the vertical bearing member 36^a of the arm 36. Adjacent to the outer end of the arm 36 is mounted to swing thereon, about a vertical axis 38, a second horizontally extending arm 39. At the outer end of this arm 39 is mounted the clipping mechanism to clip the surface of the hat 20. Connected adjacent the outer end of the arm 39, in a manner to be more fully described herein, is a rope or cable 40, which passes around a post 41 (Fig. 1), thence over a pulley 42 and downwardly through the hollow bearing member 36^a. At the lower end of the cable 40 are carried adjustable weights 43.

By means of the mechanism just described, as the rack 31 is slowly reciprocated by the rotation of the worm wheel 24, the clipping mechanism carried at the outer end of the arm 39 is moved in a horizontal path of traverse about the crown of the hat 20. The weights 43 hold the clipping mechanism in against the surface of the hat, and the pressure of the clipping mechanism against the hat may be adjusted by adjusting the weights 43. By adjusting the connection between the crank arm 28 and the worm wheel 24, by moving the bolt 26 along the slot 27, the length of the reciprocations of the rack 31, and hence the length of the path of movement of the clipping mechanism, may be adjusted. Also, by suitable adjustment of the connection between the bracket 30 and the rack 31, the clipping mechanism may be made to travel between any two desired points for a given length of movement, for example, the clipping mechanism may be made to travel between the tip of the hat and the band or brim on one side, or it may be made to travel from the band of the hat on one side, across the tip and to the band of the hat on the other side, or it may be made

to travel between any two desired intermediate points.

Considering now the clipping device or clipping mechanism more particularly, reference is had to Figures 1 and 2. The operating or cutting portions of the clipping mechanism comprise a rotating cutter 44, and a bed plate or bed knife 45 co-acting with the rotating cutter blades. When the clipping mechanism is operative the bed knife 45 rests against the hat surface, and the thickness thereof at its operative edge determines the length to which the nap of the hat is cut. The structure of a fur felt hat body consists of fur and hair fibres which, in the process of manufacture, are caused to closely and tightly interlock and interlace. In the preparation of a hat body for a velour finish, some of the fur fibres and hair fibres in the outer layers on the outer surface of the hat are loosened by brushing or scratching and are thereby caused to project out from the main body at varying lengths. The purpose of the clipping operation is to evenly clip these protruding fibres to a uniform length so as to produce a finish having an appearance similar to that of velvet. In clipping a surface which is rounded or otherwise not flat, such as the surface of the crown of the hat, it is difficult to clip the nap or projecting fibres to a uniform length and avoid digging into the body of the hat or injuring the finish. The machine illustrated herein is adapted to uniformly clip all portions of the rounded surface of the crown of a hat, such as a hat 20, with rapidity and without requiring manual skill. As the hat 20 rotates, the clipping device is traversed at a proper rate of speed across the surface of the crown in a path extending between the band and the tip, and, during this traverse the rotating cutter 44 and the co-acting bed knife 45 are continually operative upon the hat surface to dependably and uniformly clip the nap.

Turning again to the clipping mechanism, the rotating cutter 44 and its bed knife 45 are carried in or upon a casing 46. The casing 46 has a downwardly projecting hollow portion 46^a which is pivoted upon a vertical post 47 projecting upwardly from the end portion of the arm 39. As shown herein the post 47 is secured in an opening in the arm 39 by means of a set screw 48. Secured to the bottom portion of the part 46^a of the clipper frame is a collar or bracket 49 having a projecting arm 50 to which the rope or cable 40 is connected. The clipping device is thus mounted to tilt about the vertical axis of the post 47 as it traverses over the surface of the rotating hat crown. As mentioned above, the cable 40, under the pull of the weights 43, continually urges the clipping device into operative engagement with the hat, holding the bed knife 45 against the hat surface with the pressure

required for uniform operation. In addition, the cable 40, acting through the arm 50, tends always to hold the clipping mechanism in such position during its traverse that the hat contacting surface of the bed knife 45 is at the proper angle to a line passing between the post 47 upon which the clipping mechanism swivels and the post 41 around which the cable 40 passes. The cable 40 thus controls the swiveling of the clipping mechanism about the bearing post 47 and serves to keep the bed knife 45 always in proper contact with the hat surface; also this same action of the cable 40 prevents the clipping mechanism from sudden tilting about the post 47 at any point in its traverse, for example, it prevents a sudden tilting of the clipping mechanism as it passes over the "square" of the hat. The pivotal mounting of the clipping mechanism upon the post 47, in conjunction with the control thereof by the cable 40, thus insures that all portions of the hat crown will be acted upon by the rotating cutter and dependably clipped.

As is seen in Figure 2, the bracket 49 to which the cable 40 is attached is adjustably secured to the clipper portion 46^a as by means of a screw 51 and slot 52. The projecting arm 50 may thus be adjusted in position about the axis of the post 47. By means of this adjustment the cable 40 may be made to act upon the clipper through an arm of force which tends to swing the clipper about the post 47. In use, the bracket 49 is preferably so adjusted that the cable 40 tends to tilt the clipper about the post 47 as the clipping mechanism approaches the band of the hat, and tends to tilt it so that the portion of the clipper nearest to the band is drawn inwardly with increasing pressure. Thus it is assured that the surface of the crown will be dependably clipped all the way up to the brim. The post 41 around which the cable 40 passes is preferably provided with a roller 53 which provides an anti-friction bearing for the cable. The post 41 is formed upon a plate 54, which has formed thereon also ears 55 in which pulley 42 is carried. As shown in Figure 3, the plate 54 is secured to the arm 36 by means of a bolt 56 passing through a slot 57 in the plate, the slot being arcuate and generated about the axis of the arm 36. The plate 54 may thus be adjusted to bring the post 41 into different positions for adjusting the direction of pull of the cable 40 upon the clipping mechanism.

Turning again to Figures 1 and 2, mounted upon the clipper casing 46, by means of a suitable saddle 58, is a small electric motor 59. This motor thus moves with the clipper and is connected to drive the rotating cutter 44 as by means of a belt 60 passing over a pulley 61 on the motor shaft and a pulley 62 on the cutter shaft. The clipper casing 46 is hollow, and connected to the rear side thereof

is a pipe 63 for carrying away the clippings removed by the cutter. To this pipe 63 is connected a flexible pipe or hose 64 which passes downwardly to a blower 65. The blower 65 is conveniently mounted upon a framework 66 extending between the cross members 13 of the frame and beneath the table or platform 11. The blower is driven from the driving motor 21 as by means of a belt 67. The blower 65 creates a strong suction drawing air inwardly about the co-acting edges of the rotating cutter and its bed knife, downwardly through the flexible pipe 64, and discharging through a pipe 68. This suction removes the clippings and at the same time assists in causing the fur fibres to stand up in position to be cut off by the clipper.

On the upper side of the clipper casing 46 is mounted a nozzle 69 which is connected through a valve 70 with a hose 71. The hose 71 is supplied with compressed air, as will be more fully described, and the nozzle 69 directs this compressed air in a stream against the hat surface just in advance of the co-acting cutter and bed knife. As shown in Figure 3 the nozzle 69 is of a width commensurate with that of the width of the bed knife and axial length of the rotating cutter. The stream of air directed at high pressure by the nozzle 69 against the hat surface loosens up the fur fibres which may be matted down, so that they are placed in proper condition for efficient action thereon by the clipper, and the stream of air also cleans the nap of any foreign material.

From the foregoing it will be seen that the clipping mechanism, with its driving motor 59, is caused to travel over the crown of the rotating hat in a manner to dependably clip all portions of the crown. During the action of the clipping device the nap of the hat is continually placed in proper condition for efficient action by the clipper and the clippings removed by the cutter are continually removed and disposed of. The mounting of the driving motor directly upon the clipper frame to traverse therewith is distinctly advantageous. Only a small motor is required to drive the clipper at the required high speed. The use of flexible driving shafts and such cumbersome equipment, together with the loss of power occasioned thereby, is avoided. The yielding pressure exerted by the cable 40 in holding the clipping device against the hat insures continual proper engagement between the bed knife 45 and the hat surface, and also prevents any possibility of too great pressure which might cause the bed knife to dig into the hat and injure the hat body. It will be seen that this clipping machine is one which is thoroughly practical and capable of producing a high grade of work in a rapid and entirely dependable manner.

As has been mentioned above, the machine may be adjusted so that the clipping de-

vice will travel between any two desired points in a path between the band of the hat on one side and the band of the hat on the opposite side. In hat clipping it is advantageous to first clip the hat while the clipper and the hat surface are moving in one direction with respect to each other, and to then clip the hat while the clipper and the hat surface are moving in the opposite direction with respect to each other. A more thorough clipping can be achieved upon the indiscriminately arranged fur fibres by employing this two-way clipping.

Referring again to Figure 1 of the drawings, as has been described, the shaft 17, by which the hat block 19 is driven, is adapted to be driven from the driving shaft 16. Upon the forward end of the driving shaft 16 is a bevel gear 72, which is conveniently formed integrally with the worm gear 23, the worm gear being formed upon the elongated hub portion 73 of the bevel gear 72, and this member being fastened to the shaft 16 as by means of pins 74. The rear end 17^a of the shaft 17 projects into and is loosely supported in the forward end of the hub 73. The gear 72 meshes with a bevel gear 75 which is secured upon a shaft 76 projecting upwardly and having a bearing in a bracket 77 of the frame. The gear 75 meshes also with a bevel gear 78 which is loosely mounted upon the shaft 17 to rotate thereon. Thus the gear 72 is rotated in one direction and the gear 78 is rotated in the opposite direction, with respect to the common axis of shafts 16 and 17. Splined upon the shaft 17 between the two gears 72 and 78 is a member 79 which has a clutch face at each end thereof. The forward face of the gear 72 is shaped to mate with the rear clutch face of the member 79, and the rear face of the gear 78 is shaped to mate with the forward end of the member 79. In the surface of the clutch member 79 is formed a circumferential groove in which is positioned a collar 80 having trunnions 81 and 82 (Figure 3) projecting from the sides thereof. Extending rearwardly from the trunnion 81 is an arm 83, and, on the opposite side of the frame, is a corresponding arm 84 extending rearwardly from the trunnion 82. The arms 83 and 84 are connected respectively at their rear ends to the downwardly projecting arms 85 and 86 of a hand lever 87. The lever 87 is fixed upon a pin 88 which has a bearing 89 on the top of the frame, the two arms 85 and 86 straddling the top of the frame. By swinging the lever 87, the clutch member 79 may thus be moved into driving engagement with the gear 72 or into driving engagement with the gear 78 or to an intermediate position in which it engages neither of the gears. As shown in Figure 1, there is positioned in the arm 85 a spring-pressed pin 90, and in the frame are provided three holes to receive the pin. By

means of this pin and the three holes the clutch member 79 is positioned and held in any of the three positions mentioned above. In the position of the parts shown in the drawing, the clutch member 79 is in engagement with the gear 72, so that the hat 20 is driven in the direction of rotation of the shaft 16. By swinging the lever 87 to the other extremity of its movement, the clutch member 79 may be moved into engagement with the gear 78 to drive the hat in the opposite direction of rotation.

The means thus provided for reversing the direction of rotation of the hat, and the means provided for adjusting the path of travel of the clipping mechanism, makes it possible to give the hat the advantageous two-way clipping by means of this machine. The mechanism is first adjusted so that the clipper moves between the tip of the hat and the band on one side, the rotation of the hat being such that the hat surface approaches the cutter in the proper direction which is, in this instance, downwardly. Thereafter the mechanism is so adjusted that the clipper moves between the tip and the band on the opposite side of the hat, and the direction of rotation of the hat is reversed, so that the hat surface still approaches the clipper in a downward direction. Thus, with very convenient adjustments, the hat surface may be clipped in two directions if it is desired.

Considering now the mounting of the hat block 19, the block shown herein is provided with an interiorly threaded metal bushing 91 which is secured in the block as by means of screws 92. In order to mount the hat block, with the hat thereon, in position upon the machine, this bushing is threaded upon a projecting spindle 93 and against a shoulder 94 thereon. Secured to the forward end of the shaft 17 is a hollow member 95 into which is received the rear end 96 of the spindle 93. The part 96 is provided in its surface with a longitudinal groove 97 and it is secured in position in the member 95 by means of set screws 98 threaded through the member 95 and entering the groove 97. The spindle 93 is thus adjustable into and out of the member 95 by loosening the screws 98 and sliding the part 96 inwardly or outwardly. This adjustment provides for positioning the hat forwardly or rearwardly with respect to the axis about which the arm 36 swings. Such an adjustment is desirable in order to permit the swinging arms 36 and 39 to properly function in operating upon hats of various depths of crown.

The hats which are to be clipped upon this machine, and particularly ladies' hats, vary greatly in depth of crown, and the provision of means for adjusting relatively the position of the hat and the position of the axis about which the arm 36 swings make it pos-

sible to accommodate the machine to all of the various styles.

As shown in Figure 1, the bracket 35, in which the arm 36 is swiveled, is adjustable in position forwardly and rearwardly relative to the hat. The inner end 35^a of the bracket or supporting member 35 is slidably received in a hollow part 14^a of the frame and is clamped therein by means of set screws 14^b which are threaded through the part 14^a and engage a groove 35^b. Thus the position of the axis about which the arm 36 swings is adjustable lengthwise of the axis of rotation of the hat, and the hat support is also adjustable in the same direction. By these adjustments the hat and the axis of the arm 36 may be very conveniently brought into the proper relation for efficient action of the clipper upon hats of any depth of crown.

Turning again to the driving mechanism of the machine, the shaft 25, upon which the worm wheel 24 is mounted, is supported in arm 100 (Figures 3 and 4), and this arm 100 is pivoted upon the frame 14 at 101 adjacent the rear thereof. The forward end of arm 100 is connected by a link 102 with a pin 103 which is eccentrically positioned upon a shaft 104. The shaft 104 extends through the frame 14, having a bearing therein, and has fixed upon its other end a lever 105. By turning the lever 105 the eccentric pin 103 is turned about the axis of the shaft 104 so as to raise or lower the arm 100 and hence to raise or lower the worm wheel 24 which is supported thereby. Thus, by means of the lever 105 the worm wheel is moved into or out of engagement with the worm gear 23 to start or stop the drive of the clipper traversing mechanism. Formed upon lever 105 is a projection 106 which engages a part 14^c of the frame to limit the movement of the lever in a direction to raise the worm wheel.

Referring now to Figure 1, the lever 105 has a downwardly projecting portion 105^a to which is connected a downwardly extending rod 107. The rod 107 is connected at its lower end 108 to a lever 109, forming part of a valve 110. The valve 110 controls the flow of air through the pipe 71 to the nozzle 69 on the clipper. The valve is conveniently mounted upon the frame portion 11 of the machine and is connected with a suitable source of compressed air by means of a pipe 111. From the valve the air is led through a pipe 112 and through a fitting 113 to the flexible pipe or hose 71 which passes to the nozzle. When the hand lever 105 is operated to start the drive of the worm wheel 24 and hence to start the traversing movement of the clipper, the valve 110 is opened by the connections described, to start the flow of air from the nozzle against the hat. When the worm wheel is dropped out of engagement with the worm, thereby to interrupt the

traversing movement of the clipper, the air is shut off.

In order to draw the clipper out of engagement with the hat, the arm 39 is swung outwardly about its pivot 38. As shown in Figure 3, the end of the arm 39 is shaped to provide a handle 39^a which may be grasped conveniently to swing the clipper to an inoperative position.

The clipper is held in this inoperative position by means of a pin 114 which is carried in a lug 115 on the arm 39 and the lower end of which rides upon a ledge 116 projecting outwardly from the arm 36. When the arm 39 is swung outwardly to carry the clipper to its inoperative position, the pin 114 drops into an opening 117 to hold the arm and the clipper in such position.

Referring particularly to Figures 5 and 6, there is pivoted upon a pin 118, projecting outwardly from the side of the arm 39, a link 119 having an arm 120 which projects beneath the head of the pin 114. The link 119 is connected by a rod 121 with a thumb lever 122 pivoted upon the arm 39 by pin 123 and positioned adjacent to the handle 39^a. By depressing the thumb lever 122 the pin 114 is raised from the opening 117 to permit the clipper to swing into engagement with the hat under the urge of the cable 40. With one hand the operator may thus grasp the handle 39^a and depress the thumb lever 122, in moving the clipper toward the hat. The other hand of the operator is thus free to guide or steady the clipper as it comes into contact with the hat or for any other purpose. The rotating cutter is driven at high speed and there is danger that the hands of the operator might accidentally come into contact with the rapidly moving cutter blades if the drive of the clipper were continuous while the operator is placing a hat in position or removing a clipped hat. Still referring to Figures 5 and 6, there is secured upon the end portion of arm 36 a switch 124 which controls the current to the clipper driving motor 59. The wiring leading through the switch to the motor is shown at 125 in Figure 1. The switch is operated by a button or plunger 126, which projects outwardly toward the lug 115 of the arm 39. The button 126 is spring pressed outwardly, and, when it is in its outer position, the circuit of the motor is closed. When the arm 39 is swung about its pivot 38 to move the clipper away from the hat, the lug 115 presses the button 126 inwardly and opens the switch to interrupt the drive of the motor 59. The dropping of the pin 114 into the opening in the ledge 116 locks the arm 39 in its outer position, as has been described, and this also locks the button 126 in its inner position to break the circuit of the motor.

As soon as the clipper is moved to its operative position the switch closes and the drive of the clipper is started.

From the foregoing it will be seen that there is here provided a machine which achieves the objects of this invention and accomplishes advantages of real practical value. The machine is capable of uniformly and dependably clipping the crowns of velour hats rapidly and accurately. The machine is practical throughout and simple in construction, and it is capable of operating efficiently without requiring skilled attendants.

As many possible embodiments may be made of the above invention, and as many changes might be made in the embodiment above set forth, it is to be understood that all matter hereinbefore set forth or shown in the accompanying drawings is to be interpreted as illustrative and not in a limiting sense.

I claim:

20. 1. In a hat clipping machine, in combination, means for supporting a hat block having a hat thereon, means for rotating said hat block and said hat, a clipping device, means for driving said clipping device rigidly mounted with respect thereto, means for supporting said driven clipping device in position to clip the surface of said hat, and means for driving said clipper supporting means to cause said clipping device to traverse the surface of the crown of said rotating hat, said clipping device being mounted upon said supporting means for tilting thereon during said traverse about an axis substantially transverse to the path of said traverse.
35. 2. In a hat clipping machine, in combination, means for supporting a hat block having a hat thereon, means for rotating said hat block and said hat, a clipping device comprising a rotary cutter and coacting bed-knife, means for rigidly supporting said clipping device in position to clip the surface of said hat, means for driving said supporting means to cause said clipping device to traverse the surface of the crown of said rotating hat with said coacting cutter and bed-knife in operative engagement therewith, an electric motor mounted upon said supporting means and moving therewith, and with said clipping device and connected to drive said rotary cutter and means adapted to coact with said supporting means to open said motor circuit when said clipping device is moved out of operative engagement with said hat.
50. 3. In a hat clipping machine, in combination, means for supporting a hat block having a hat thereon, means for rotating said hat block and said hat, a clipping device, means for driving said clipping device, means for supporting said driven clipping device in position to clip the surface of said hat, and means for driving said clipper supporting means to cause said clipping device to traverse the surface of the crown of said rotating hat, a nozzle carried by said supporting means

adjacent to said clipper and moving therewith and directed against the hat surface, means for leading to said nozzle a stream of air under pressure and means for automatically controlling the admission of air to said nozzle.

4. In a hat clipping machine, in combination, means for supporting a hat block having a hat thereon, means for rotating said hat block and said hat, a clipping device comprising a driven cutter, means mounted relatively immovable with respect to said clipping device for driving said cutter, means for supporting said clipping device in position to clip the surface of said hat, and means for relatively moving said supporting means for said clipping device and said supporting means for said hat to cause said clipping device to traverse the surface of the crown of said rotating hat in a path extending between the band and the tip of said hat, said driven cutter being mounted upon said clipper supporting means for tilting movement during said traverse about an axis substantially transverse to the line of said traverse.

5. In a hat clipping machine, in combination, means for supporting a hat block having a hat thereon, means for rotating said hat block and said hat, a clipping device comprising a driven cutter, means for driving said cutter disposed in rigid relation to said clipping device, means for supporting said clipping device in position to clip the surface of said hat, and means for relatively moving said supporting means for said clipping device and said supporting means for said hat to cause said clipping device to traverse the surface of the crown of said rotating hat in a path extending between the band and the tip of said hat, and means for rigidly holding said clipping device and said hat in operative engagement with any desired part of said hat during said traverse.

6. In a hat clipping machine, in combination, means for supporting a hat block having a hat thereon, means for rotating said hat block and said hat, a clipping device, means disposed in a relatively immovable position therewith for driving said clipping device, means for rigidly supporting said clipping device in position to clip the surface of said hat, and means for driving said clipper supporting means to cause said clipping device to traverse the surface of the crown of said rotating hat, and a flexible pipe connected to said traversing clipping device for removing therefrom the clippings cut thereby.

7. In a hat clipping machine, in combination, means for supporting a hat block having a hat thereon, means for rotating said hat block and said hat, a clipping device comprising a driven cutter, means for supporting said clipping device in position to clip the surface of said hat, an electric motor mounted

- on said supporting means for driving said cutter, means for relatively moving said clipping device supporting means and said hat supporting means to cause said clipping device to traverse the surface of said hat, said clipping device being mounted for movement into and out of engagement with said hat, and means responsive to movement of said clipping device out of engagement with said 5 hat adapted to open the circuit of said motor.
8. In a hat clipping machine, in combination, means for supporting a hat block having a hat thereon, means for rotating said hat block and said hat, a clipping device comprising a driven cutter, means for supporting said clipping device in position to clip the surface of said hat, means for driving said cutter, means for relatively moving said clipping device supporting means and said hat 10 supporting means to cause said clipping device to traverse the surface of said hat, means for interrupting said traverse, means comprising a stream of air under pressure for loosening the fibres of the hat for the cutting 15 operation, and means responsive to interruption of said traverse adapted to cut off said stream of air.
9. In a hat clipping machine, in combination, means for supporting a hat block having a hat thereon, means for rotating said hat block, an arm mounted to swing about an axis substantially transverse to the axis of rotation of said hat block, a clipping device, means mounting said clipping device upon 20 said arm and in a position to clip the crown of said hat, means for swinging said arm about said axis thereof to cause said clipping device to traverse the crown of said rotating hat, means for adjusting the position of said hat 25 support in a direction lengthwise of the axis of rotation of said hat and means for adjusting the position of said axis of said arm in a path parallel to the axis of rotation of said hat.
- 45 10. In a hat clipping machine, in combination, means for supporting a hat block having a hat thereon, means for rotating said hat block, an arm mounted to swing about an axis substantially transverse to the axis of 30 rotation of said hat block, a clipping device, means mounting said clipping device upon said arm and in a position to clip the crown of said hat, means for swinging said arm about said axis thereof to cause said clipping device to traverse the crown of said rotating hat, and means for adjusting the position of the axis of rotation of said arm in a direction substantially parallel to the axis of rotation 35 of said hat.
- 50 11. In a hat clipping machine, in combination, means adapted to support and rotate a hat, a clipping device positioned to clip the surface of said rotating hat as said surface moves thereby, means for reversing the direction of rotation of said hat, and means 40 for moving said clipper to such position that the moving hat surface moves relative to the operative clipper element in substantially the same direction as prior to said reversal.
- 55 12. In a hat clipping machine, in combination, means adapted to support a hat block having a hat thereon, means for rotating said hat block and hat, a clipping mechanism adapted to clip the hat surface and comprising a rotary cutter, an electric motor for driving said rotary cutter, means comprising two relatively rotatable levers on which said clipping device is mounted for movement into and out of engagement with said hat, means for relatively moving said hat block and said 55 clipping device to cause said clipping device to traverse the surface of said hat, a switch normally closing the circuit of said motor mounted upon one of said levers, and means on the other of said levers adapted when said clipping device is moved out of engagement with said hat to open said switch thereby to interrupt the drive of said rotary cutter.
- 60 13. In a hat clipping machine, in combination, means for supporting a hat block having a hat thereon, means for rotating said hat block and said hat, a clipping device comprising a driven cutter, means for driving said cutter, means mounting said clipping device to clip the surface of the crown of said 65 rotating hat, means for relatively moving said hat and said clipping device to cause said clipping device to traverse the surface of said hat crown in a path extending at substantially right angles to the brim, means for adjusting said last means to adjust the range of said traverse, and means for reversing the direction of rotation of the hat.
- 65 14. In a hat clipping machine, in combination, means for supporting a hat block having a hat thereon, means for rotating said hat block and said hat, a clipping device adapted to clip the surface of said hat, a swinging arm upon which said clipping device is mounted for movement into and out of engagement with said hat, means for holding said arm in a position in which said clipping device is out of engagement with the hat, means adapted to be gripped manually to swing said arm, and means positioned adjacent to said last means to be manually operated in conjunction with said last means to release said holding means.
- 70 15. In a hat clipping machine, in combination, means for supporting a hat block having a hat thereon, means for rotating said hat block and said hat, a clipping device, an electric motor for driving said clipping device rigidly mounted with respect to said clipping device, means for supporting said driven clipping device in position to clip the surface of said hat, and means for driving said clipper supporting means to cause said clipping device to traverse the surface of the 75 crown of said rotating hat, said clipping device 80

- vice and said motor being mounted upon said supporting means for tilting thereon, whereby said clipping device is enabled to meet all parts of the surface of said hat at a proper angle and be continuously driven.
16. In a hat clipping machine, in combination, means for supporting a hat, means for rotating said hat, a clipping device comprising a rotary cutter and a coacting bed-knife, means for supporting said clipping device in position to clip the surface of said hat, an electric motor disposed in rigid relation to said clipping device for driving said rotary cutter, means for relatively moving said clipping device and said rotating hat to cause said clipping device to traverse the surface of the crown of said hat, and means for yieldingly holding said clipping device against said hat, said clipping device and said motor being pivoted upon said supporting means therefor to swivel thereon during said traverse about an axis transverse to the axis of said rotary cutter, whereby said bed-knife is yieldingly pressed into operative engagement with said hat at all points of contact therewith, and continuous rotation is imparted to said rotary cutter.
17. In a hat clipping machine, in combination, means adapted to support and rotate a hat, a clipping device positioned to clip the surface of said rotating hat as said surface moves thereby, means for reversing the direction of rotation of said hat, means for moving said clipper to such position that the moving hat surface moves relative to the operative clipper element in substantially the same direction as prior to said reversal, and an electric motor rigidly mounted with respect to said clipping device and adapted to impart to said clipping device uninterrupted rotation in one direction.
18. In a hat clipping machine, in combination, means for supporting a hat, means for rotating said hat, clipping means comprising a rotary cutter, means comprising two relatively rotatable levers for supporting said clipping device in position to clip said hat, an electric motor mounted upon one of said levers and connected to drive said cutter, a switch carried by one of said levers, and means on the other of said levers adapted to coact with said switch to open the circuit of said motor when one of said levers is swung upon the other to throw said clipping means out of operative contact with said hat.
19. In a hat machine, a rotary hat support, means for operating said support, means adjacent said support for performing a finishing operation on a hat mounted on said support, means for shifting said finishing means longitudinally of the hat surface while the hat is being rotated, a detachable driving connection from said first means to the said shifting means, a personally operated means for controlling said connection, means for supplying a fluid to the surface of the hat adjacent said finishing means, and means operated by said personal means for controlling the supply of fluid.
- In testimony whereof, I have signed my name to this specification this 16th day of September, 1927.
- JAMES F. DORAN.
- for controlling said connection, means for supplying a fluid to the surface of the hat adjacent said finishing means, and means operated by said personal means for controlling the supply of fluid.
- In testimony whereof, I have signed my name to this specification this 16th day of September, 1927.
- JAMES F. DORAN.
